LATCH FOR DOORS

George W. Wells, Amesbury, Mass.

Application March 26, 1935, Serial No. 13,032

20 Claims. (Cl. 292—169)

This invention relates to latches which are primarily designed for use in connection with doors of automobile bodies and which, in some respects, may be considered as an improvement on the construction of my prior Patent No. 1,738,338 of December 3rd, 1929, in which the jamb-engaging member of the latch is provided with a rigid projection, which performs the function of a door holder, or "dovetail", and which is also adapted to be locked against opening in a multiplicity of positions.

The primary objects of my invention are to provide a construction having all the advantages of said prior construction, and which will be less difficult to manufacture, so that the cost of manufacture may be reduced and also will be more durable, and will not be affected by wear, so that replacements will not be necessary after long periods of use.

I accomplish these objects by means of the construction hereinafter described and as illustrated in the accompanying drawing in which:

Fig. 1 is a combined side elevation and sectional view of a portion of a door and its jamb, provided with a latch embodying my invention.

Fig. 2 is a plan view, partly in section at line 2—2 of Fig. 1.

Figs. 3 and 4 are detail sectional views at line 3—4 of Fig. 2.

Fig. 5 is a detail sectional view at line 5—5 of Fig. 3.

Fig. 6 is a view in elevation of a portion of the edge of the door.

Fig. 7 is a detail view of a portion of the latch operating means.

Fig. 8 is a detail view of the locking and remote control means.

Fig. 9 is a detail view of the handle operating means.

Figs. 10 and 11 are detail sectional views at line 10—11 of Fig. 1.

Fig. 12 is a detail view of one of the striker plates.

Fig. 13 is a detail view at line 13—13 of Fig. 3.

In the drawing, a portion of a door 14 and its jamb 16 are indicated, and, as it will be understood that the door swings horizontally on hinges in the usual manner, further illustration thereof will be unnecessary.

The door is provided with the usual channel shaped metal edge pillar 18 and the latch operating means are mounted on a similarly shaped metal casing 20 which is fitted into and secured to the inner side of said pillar.

A rigid, rectangularly shaped projection 22 is

permanently connected by welding to the middle portion of casing 20 and extends through a similarly shaped aperture formed in the face or middle side of the pillar 18, which forms the edge of the door, as shown in Figs. 1, 2, 5 and 6, said projection 22 having a horizontal bottom face which is arranged to engage the supporting face of the striker casing as hereafter more fully described, so that the door will be rigidly supported thereby when closed.

The top portion of projection 22 which extends beyond the outer side of pillar 18 is cut away, forming a notch having a horizontal top face 23 and a vertical end face 24 thereon which is approximately flush with the outer surface of the pillar 18, as shown in Fig. 1, and a recess 25 is formed in said projection which extends from the inner side of casing 20 and terminates at the front wall of said projection, said recess having a semi-cylindrical bottom and vertical sides 20 extending to the top surface 23, so that the recess 25 opens to the top side and inner end of the projection, as shown in Figs. 3, 4 and 5. A cam shaft 26, of the same diameter as that of the bottom of said recess 25 is rotatably mounted 25 on the bottom thereof, and one side portion of said shaft, which extends from its outer end to the face 24, is cut away to form a recess 27 therein and an approximately radially disposed cam face or shoulder 28. The inner end portion 29 of shaft 26 is rigidly connected to the middle of a flat plate 30, which is located in close proximity to the inner side of the middle or bottom portion of the casing 20, and extends at each side thereof to form a pair of oppositely extending 30 arms, one of which is provided with a rigid lug 31 and the other of which is provided with a rigid lug 32, as shown in Figs. 1, 2, 5 and 7. A square shaft 34, having a handle 35 on its outer end externally of the door, is mounted in a bushing 36, 40 which is rotatably mounted in the outer side of casing 20 (see Fig. 2) and an arm 38 is rigidly connected to the inner end of said shaft by a screw 39 (Fig. 9), said arm having its end portion arranged to engage the lug 31 on plate 30, 45 so that when shaft 34 is rotated by its handle 35, the shaft 26 will be rotated to a limited extent.

A vertically movable latch member 40 is mounted in the notch on the top side of projection 22, and when in the lowest position thereof its bottom side rests on the face 23 and its rear edge engages the end face 24, so that it completely fills the notch, and a pair of guiding pins 42 are secured to and projected vertically from 55

the under side of said member, said pins being slidably mounted in holes 43 formed in the sides of projection 22, so that said member is rigidly held against horizontal movement relative to said projection and is guided thereby in its vertical movements, the sides of said pins each having a flattened portion to form shoulders 44, which are arranged to engage stop pins 45 fixed in the projection 22 (see Fig. 13), to limit the upward movement of said latch member and provide a permanent connection with the projection 22. The top surface 46 of the member 40 is horizontal and extends for the length and width thereof and the under side of said member 40 has a transverse projection 48 depending therefrom having a shoulder 49 at one end, which is arranged for engagement by the cam face 28 on the shaft 26, and a concave face on its lower end, corresponding in curvature to that of the surface of said shaft, the arrangement being such that when the parts are in the position of Fig. 4 and the shaft 26 is then turned to the position of Fig. 3, pressure of face 28 against shoulder 49 will cause the latch member 40 to be raised to the position of Fig. 3, in which position the member will be rigidly supported by the shaft.

A spring arm 50 is mounted on casing 20 and arranged to engage one of the arms of plate 30 (see Fig. 7) and acts to rotate the shaft 26 in the direction first to raise the latch member from its lowest position, in which it rests on the face 23 of projection 22, to its highest position shown in Fig. 3 and to continue the rotation of said shaft until its shoulder 28 is carried for a substantial distance beneath the projection 48, this movement by spring 50 being limited by a stop pin 51 in casing 20, which engages arm 38 (see Fig. 9). With this arrangement it will therefore be necessary to turn the handle 35 fully half the distance through which it may be turned before the cam face 28 is moved past shoulder 43 to permit the latch member to be lowered.

A supplemental means is provided for operating shaft 26 from the inner side of the door, usually termed the remote control, which comprises a lever 52, which is mounted on a pivot 53 in the inner side of casing 20 and is provided with an arm 54 which is arranged to engage the lug 32 on plate 30. A link 55 is connected to said latch by a pivot 56 and has a handle 57 thereon which projects internally of the door, (see Figs. 2 and 8), so that when the link is pulled, the arm 54 will swing the plate 30 in the direction to rotate shaft 26 to permit the latch member 40 to be lowered. The lever 52 is also provided with a tooth 58 which, when the link 55 is pushed towards the edge of the door to its fullest extent, will extend beneath the under side of plate 30, so that if it should be attempted to turn the handle 35, so as to lower the latch member, this movement will be prevented. The lever 52 thus has three positions viz a locking position, shown in Fig. 8, an operating position in which it has acted to lower the latch member and an intermediate position in which operation by the exterior handle 35 is permitted. A small spring 59 is engaged with the shaft 34 and acts to hold arm 38 against stop pin 51 when shaft 26 is operated by the remote control means 55.

As shown in Figs. 10 and 11 the striker member, which cooperates with the projection 22 and latch member 40 above described, comprises a rectangular shaped casing 60, which is set into the jamb, and is provided with a horizontal supporting portion 61, having a downwardly inclined

outer end, so arranged that the under side of the projection 22 will engage said inclined end as the door is closed, and ride up on the same, so that when the door is fully closed, it will be firmly supported thereon, and the top face 46, of the latch member 40, will thus be held at a predetermined level with relation to the striker means now to be described.

A series of striker fingers, or plates 62 cooperate with face 46 to hold the door closed, said plates being arranged side by side and suspended at their upper ends on a rod 64, which extends horizontally between, and is supported by the front and rear walls of the striker casing, said rod passing loosely therethru, so that said plates may swing inwardly thereon to a limited, but sufficient extent.

Each plate 62 has a pair of rounded projections 63 on its inner side, arranged at the same level, as shown in Fig. 12, the projections on the outermost plate being arranged close to the upper end thereof and on the other plates at successively lower levels with respect to the outermost plate, as shown in Figs. 10 and 11. A coil spring 65 is interposed between the innermost plate and the inner wall of the casing 60 and engages said plate at a distance below the level at which the plate engages the projections 63 on the next plate in front. With this arrangement the spring 65 acts to swing all the plates outwardly, so that the outermost plate is held against the outer wall of casing 60 in an approximately vertical position as shown in Fig. 10, and the lower ends of said plates are held in engagement with each other successively, the outermost plate acting as a stop for the others, and said projections 63 acting to hold said plates separated above their lower ends, so that they are slightly inclined forwardly from their upper ends as shown in Fig. 10. As thus arranged each plate is pivotally engaged with the next adjacent by means of projections 63. The lower ends of plates 62 are preferably beveled to a sharp edge from their inner to their outer sides, and the top ends thereof are similarly beveled and engaged with the under surface 66 of the top side of casing 60, so that each plate has a knife edge pivot at its upper end and a sharp edge at its lower end. Said plates 62 are of rigid hardened steel, or other suitable wear-resisting material.

As said plates 62 are all duplicates except as to the location of projections 63 and the sharp lower edges thereof are all disposed in a plane which is approximately horizontal, and which is slightly below the level of the top surface 46 of the latch member, when in raised position, and when the supporting projection 22 thereof is resting on the surface 61 of the striker casing. Consequently, as the door swings inwardly towards its fully closed position, the striker plates are engaged by the latch 40 and swung inwardly to a sufficient extent to permit the latch to pass thereunder, as shown in Fig. 11. In this position the spring 65 acts to press the sharp edge at the lower end of each plate firmly against the top surface of the latch, and, as the top ends of said striker plates are firmly engaged with the striker casing, it will be apparent that any tendency of the door to move outwardly will cause the striker plates to bite into the top surface 46 of the latch, which will be preferably made of soft steel, so that the door will be positively locked against opening movement. With the arrangement shown, the greater the tendency to force the door open, the greater will be the force with which the striker

plates will be engaged with the latch, so that all tendency to force the door open will be effectively resisted. The entire top surface of the latch member may be smooth, but a safety groove 5 67 is preferably formed therein and additional grooves may be provided if desired, but will ordinarily be unnecessary, as slight indentations will be formed in surface 46 by use. Under all conditions, however, the door will be firmly locked 10 against opening movement in any position to which it may be moved after it has been closed to a sufficient extent to permit one of the striker plates to be engaged with the surface of the latch member, assuming, of course, that the latch member 15 is held in its raised position shown in Fig. 11, in which position it is rigidly supported by the shaft 26, downward pressure on the latch having no tendency to move the shaft from this position. 20 If, however, the shaft 26 is turned to the position of Fig. 4 by either handle 35 or 51, as before described, the latch 40 will be permitted to move downward to such an extent that it will be disengaged from the striker plates, so that the door 25 will be free to open. A comparatively slight movement of either handle will have no effect in permitting the latch member to be lowered, as the shaft 26 must be turned for a considerable distance before the latch will be disengaged from 30 the striker plates, so that accidental opening of the door is unlikely.

It will be apparent that the particular number of striker plates employed is not essential, as the device will operate with a single plate, but the 35 number shown is considered preferable. Also, that in the closed, or nearly closed positions of the door, in which position it may be locked by dog 58, it will be rigidly held against rattling, or movement either vertically or horizontally. 40 The surface 66 on the under side of the top portion of the striker plate is slightly inclined downward from the outer end, so that the lower ends of the plates will be held at an increasingly lower level from the outermost inward. In consequence, when the latch is carried inward, each 45 inner plate will be swung inward to a slightly greater extent than the next outer plate, so that the outermost plate will be held at only a slight forward inclination from the perpendicular to the top surface of the latch, while this inclination will be slightly increased, with respect to the other plates, from the outermost inward. It will be apparent that the locking effect of each striker 50 plate will be the greatest when in a position nearly perpendicular to the surface of the latch, as, for example, when in the position of the outermost plate in Fig. 11, so that, when in this position, there would be no necessity in having the lower end of the plate so sharp that it will bite 55 into the surface of the latch, but with the plate held in a more inclined position the necessity of having the plate sharp at its lower end would be greater.

While a single plate, held in the position of the outermost plate of Fig. 11, would be sufficient to hold the door closed, it is conceivable that, after extended use, the top surface of the latch might become worn down, so that the outermost plate might not hold at all, but as the next inner plate is held with its lower end at a slightly lower level than the outermost plate, it will engage the surface of the latch with sufficient force to lock it against outward movement. Consequently with the above described arrangement 75

provision is made for a substantial wearing down of the top surface of the latch.

It will be obvious that the same result would be secured by making each striker plate of slightly increased length from the outermost inward, or 5 by having the top surface of the latch slightly inclined upward from the outer side inward, both arrangements being equivalent constructions.

It is to be noted that all the latch operating members which are within the casing 20 are 10 located close to the sides thereof, so that they do not interfere with the window glass x, which may be extended into close proximity to the inner side of the door pillar, as shown in Fig. 2.

While the above described means for controlling the position of the latch member, is the simplest, most durable and least expensive to manufacture of any other means of which I am at present aware, it will be apparent that other means may be employed in lieu thereof without 20 departing from my invention, when considered in its broader aspects.

I claim:

1. A latch device for doors comprising a casing 25 adapted to be mounted in the edge portion of the door and having a rigid projection arranged to extend beyond the edge of the door in position to be engaged at its bottom side with a supporting face on the jamb, a latch member on the top side of said projection and guided thereby to move perpendicularly relative thereto, said member having a transversely extending face on its top side arranged for engagement with the jamb, operating means in said projection beneath said member, movable to control the 30 vertical positions thereof, and controlling means 35 for said operating means.

2. A latch device for doors comprising a casing having a rigid projection arranged to extend 40 beyond the edge of the door, a vertically movable latch member mounted on said projection having means to engage the same to guide it in its vertical movements, and having a face on its top side arranged for engagement with the jamb when in its raised position, a cam shaft 45 extending beneath said member and arranged to be moved rotatably to control the vertical positions thereof and to lock it in its raised position, an arm connected to said shaft and extending 50 transversely thereof within the casing and operating means on the casing arranged to engage said arm.

3. A latch device for doors comprising a casing having a rigid projection arranged to extend 55 beyond the edge of the door, a vertically movable latch member mounted on said projection having means to engage the same to guide it in its vertical movements, and having a face on its top side arranged for engagement with the jamb when in its raised position, operating means 60 extending beneath said latch member and movable to control the vertical positions thereof, a spring normally acting to move said operating means to hold said member in its raised position, locking means within the casing arranged 65 to be moved into a position to lock said operating means when holding said member in its raised position.

4. A latch device for doors comprising a casing 70 having a rigid projection arranged to extend beyond the edge of the door, a vertically movable latch member mounted on said projection having means to engage the same to guide it in its vertical movements, and having a face on its top side arranged for engagement with the jamb 75

when in its raised position, operating means extending beneath said latch member and movable to control the vertical positions thereof, a spring normally acting to move said operating means to hold said member in its raised position, a dog mounted within said casing and movable to one position to move said operating means in the direction to permit said member to be lowered and movable to another position to lock said operating means against such movement, and a controlling means for said dog.

5. A latch device for doors comprising a U-form casing adapted to be fitted to the edge portion of the door, said casing having a rigid projection mounted on its middle portion arranged to project beyond the edge of the door in position to engage the jamb at its bottom side, a latch member on the top side of said projection perpendicularly movable relative thereto and 10 having a face on its top side arranged for engagement with the jamb, in the raised position thereof, a cam shaft extending into said projection from the interior of said casing and having a cam face arranged for engagement with the 15 bottom side of said member and rotatably movable to control the vertical positions thereof, an arm connected to said shaft within the casing, and operating means on the casing for said arm.

6. A latch device for doors comprising a U-form casing adapted to be fitted to the edge portion of the door, said casing having a rigid projection mounted on its middle portion arranged to project beyond the edge of the door in position to engage the jamb at its bottom side, a latch 20 member on the top side of said projection perpendicularly movable relative thereto and having a face on its top side arranged for engagement with the jamb in the raised position thereof, a cam shaft extending into said projection from the interior of said casing and having a cam face 25 arranged for engagement with the bottom side of said member and rotatable to control the vertical positions thereof, an arm on the inner end of said cam shaft, a lever pivoted on one side of said casing and arranged to engage the arm of 30 said cam shaft, and means for operating said lever to operate said cam shaft.

7. A latch device for doors comprising a U-form casing adapted to be fitted to the edge portion of the door, said casing having a rigid projection mounted on its middle portion arranged to project beyond the edge of the door in position to engage the jamb at its bottom side, a latch member on the top side of said projection 35 perpendicularly movable relative thereto and having a face on its top side arranged for engagement with the jamb, in the raised position thereof, an arm connected to said shaft within the casing, a spring on the casing arranged to engage said arm and normally acting to rotate said shaft in the direction to raise said latch member and to hold it in raised position, and operating means on the casing arranged to engage said arm and to rotate said shaft in the direction to permit said member to be lowered.

8. A latch device for doors comprising a casing having a rigid projection arranged to extend beyond the edge of the doors, a vertically movable latch member mounted on said projection and having a horizontally extending face on its top side arranged for engagement with the jamb when in raised position, a cam shaft rotatably mounted beneath said member and having a cylindrical portion and a recessed portion providing 40 a radially disposed cam face adjacent thereto,

said latch member having a transverse face on its under side and a shoulder at one end of said face arranged to be engaged by said cam face on rotation of said shaft in one direction, whereby said member will first be raised and then the cylindrical portion of said shaft will be engaged with said face to provide a rigid support for the member in the raised position thereof.

9. A latch device for doors comprising a vertically movable latch member adapted to project 10 from the door and having a top face arranged for engagement with the jamb when in raised position, and adapted to be held by a downward and inward thrust thereon to hold the member against outward movement, and operating means for said 15 member arranged to control the vertical movements thereof and normally acting to hold the same in raised position and movable to permit downward movement thereof and disengagement thereof from the jamb, to permit the member 20 to move outward.

10. A latch device for doors comprising a latch member adapted to be mounted on the door and to project horizontally therefrom, said member having a jamb engaging face on its top side, and 25 operating means for raising and lowering said member normally actuated to hold the same in raised position operatively to engage the face thereof with the jamb and to be held against outward movement by an obliquely inward and 30 downward thrust of the jamb thereon, said member being downwardly movable when released by said operating means to disengage its face therefrom and permit it to move outwardly.

11. A latch mechanism for doors adapted for 35 cooperation with keeper means pivotally suspended from the jamb and having a bottom face arranged to be carried inwardly and upwardly thereby, a vertically movable latch member adapted to project from the door and having an 40 engaging face on its top side, operating means therefor arranged to control the vertical positions of said member and normally acting to hold the same in its raised position, in which position its top face is held in position to engage the 45 face of the keeper means and move the same inward and upward during its inward movement and is locked against outward movement by the inward and downward thrust of the keeper thereon, and is disengaged from the keeper when permitted to move downward by said operating means.

12. A latch mechanism for doors adapted for cooperation with a pawl pivotally suspended from the jamb, and arranged to swing inwardly from 55 the vertical, a vertically movable latch member adapted to project from the door and having a horizontally extending top face, operating means for controlling the vertical positions of said member normally actuated to hold the same 60 in its raised position, in which position the lower end of the pawl is adapted to engage said face, and by its inward and downward thrust thereon act to hold said member against outward movement and to be disengaged therefrom by downward movement of the latch member from its normally raised position.

13. A latch device for doors comprising a latch member having a horizontally disposed face arranged for engagement, a jamb member which 70 is actuated to move a face thereon obliquely outward and towards the face of the latch member, said latch member being vertically movable towards and from the jamb member between an engaging and a disengaging position, and oper- 75

ating means for controlling the vertical movements of said latch member normally actuated to hold the same in its engaging position, and operable to permit movement to its disengaged position, whereby the thrust action of the jamb member against the face of latch member may act to hold the latch member against outward horizontal movement, said movement being permitted when the latch member is permitted to move to its disengaging position.

14. A latch device for doors comprising a vertically movable latch member adapted to project from the door and having an engaging face on its top side, operating means therefor arranged to control the vertical movement of said member and normally acting to hold and lock the same in its raised position, in which position the face thereof is arranged to engage the face of a keeper on the jamb, which is adapted to be moved inwardly and upwardly by said member as the latter is moved inwardly and to move downwardly and outwardly to lock said member against outward movement, said operating means being movable to lower said member to disengage it from the face of the keeper.

15. A latch device for doors comprising a projection adapted to be rigidly mounted on the door and to extend horizontally therefrom in position to be supported by the jamb at a predetermined level, a latch member on the top side of said projection arranged to be moved vertically relatively thereto, and operating means adapted to be mounted on the door and to control the vertical movements of said member, said operating means normally acting to raise said member and lock it in raised position and said member having a face on its top side arranged for engagement with the jamb when in raised position, to hold the door closed, and to be disengaged therefrom when moved downward to permit the door to be opened.

16. A latch device for doors comprising a projection adapted to be rigidly mounted on the door and to extend horizontally therefrom in position to be engaged at its bottom side by the jamb, to support the door at a predetermined level, a latch member arranged for vertical movement on the top side of said projection and having a face on its top side, arranged for engagement with the jamb when in raised position, and operating means rotatably movable to raise

and lower said member and normally actuated to hold said member in raised position.

17. A latch device for doors comprising a vertically movable latch member adapted to project from the door and having a horizontally extending face on its top side arranged for engagement with the jamb in a multiplicity of positions of the door when the member is in raised position, to lock the door against opening movement in any of its said positions, and operating means for controlling the vertical positions of said member, normally actuated to hold said member in raised position and movable to permit the same to be lowered, and to disengage it from the jamb.

18. A latch device for doors comprising a projection adapted to be rigidly mounted on the door and to extend horizontally therefrom in position to be supported by the jamb, a vertically movable latch member mounted on said projection, and having a face on its top side arranged for engagement with the jamb when in raised position, to lock the door against opening movement and a controlling device movable within said projection beneath said member to control the vertical movements thereof and normally actuated to lock the same in raised position.

19. A latch device for doors comprising a vertically movable latch member adapted to project from the door and having a face on its top side arranged for engagement with the jamb when in raised position, a rotatably movable controlling device disposed beneath said member and having a cam face arranged to engage the under side thereof and to raise and lower the same on opposite rotational movements of said controlling device and actuating means for said controlling device normally acting to raise said member and hold it in raised position.

20. A latch device for doors comprising a vertically movable latch member adapted to project from the door and having a top face arranged for engagement with the jamb when in raised position, a cam shaft rigidly supported beneath said member and arranged for rotational movement in opposite directions to control the vertical positions of said member, and operating means for said shaft normally actuated to rotate said shaft in the direction to raise said member and to hold it in raised position.

GEORGE W. WELLS.
